UNITED STATES PATENT OFFICE

WILLIS H. POYNTER, OF BRAWLEY, CALIFORNIA, ASSIGNOR TO A. ARENA AND COMPANY, OF LOS ANGELES, CALIFORNIA, A CORPORATION OF CALIFORNIA

BOX-LINER TUCKING ATTACHMENT FOR LIDDING MACHINES

Application filed March 27, 1929. Serial No. 350,423.

The present invention relates to crate lidding machines and more particularly to a tucking attachment for the paper lining used to cover the produce packed within their 5 crate.

One of the important objects of the invention is to provide a tucking attachment of this character adapted to engage the edges of the paper lining at the front and rear 10 sides of the crate for tucking the same into position within the crate and simultaneously with the placing and securing of the lid thereupon.

A further important object is to provide 15 adjustable means for the tucking attachment which enables its use upon a crate of various sizes.

Another object is to provide an attachment of this character which may be secured 20 in operative position upon a crate lidding machine of conventional structure without necessitating any changes or alterations in the construction thereof, which at the same time is of a simple and practical construction, efficient and reliable in performance, 25 compact in its arrangement, relatively inexpensive to manufacture and otherwise well adapted for the purposes for which the same is intended.

30 Other objects and advantages reside in the special construction, combination and arrangement of the various elements forming the invention as more fully hereinafter described and claimed, reference being had to 35 the accompanying drawings forming part hereof wherein like numerals refer to like parts throughout, and in which:—

Figure 1 is a fragmentary front elevational view of a lidding machine showing the tucking attachment in position with respect thereto.

Figure 2 is a perspective view of the forward tucking member.

Figures 3, 4 and 5 are perspective views 45 of the rear tucking member and including the means for attaching the same in a stationary position to the lidding machine.

Figure 6 is a top plan view.

Figure 7 is a fragmentary vertical sec- 50 tional view through a crate illustrating the

lidder and tucking attachment in position for securing the lid and paper liner in position.

Figure 8 is a similar view showing the lidder and tucking attachment prior to en- 55 gaging the crate lid.

Figure 9 is a vertical sectional view through a crate at the completion of the lidding and tucking operation.

Figures 10 and 11 are perspective views 60 of the angle adjusting plate and the guide rod respectively for regulating the extent of inward movement of the forward tucking member, and

Figures 12 and 13 are perspective views of 65 the forward tucking member.

Referring now to the drawings wherein for the purpose of illustration I have disclosed the present invention in operative position upon a lidding machine of conventional construction, the numeral 5 designates the rear frame member of said lidding machine and with which is associated a back guard 6 and base 7 for supporting a crate of produce 8 in position upon the machine. The lidding machine also includes a lid press 9 which is carried upon the frame for vertical movement and operated in a manner well known in the art for pressing the lid 10 downwardly upon the top of the crate in order that the lid may 80 be nailed to the crate.

In packing fresh vegetables, fruits and other produce for shipment, the crate is usually provided with a paper liner indicated at 11 and space is provided at the top of the 85 crate for packing a quantity of cracked ice 12 therein to preserve the contents of the crate and over the ice is placed a liner cover 13. During the lidding operation the edges of liner 13 becomes puckered through the depressing action of the lidder in placing the lid in position and such puckering of the liner not only presents an unattractive appearance but also results in the edges of the liner becoming torn so that the cracked ice 90 will spill therefrom and dirt will be permitted to enter the crate. The present invention accordingly is intended to provide means for tucking the front and rear edges of the cover or liner inwardly of the crate and to 100

form a packing means for the cracked ice so as to prevent the bulging of the same at the front and rear edges of the crate during the lidding operation.

In carrying out the invention I provide a front tucking member 14 which comprises a horizontally disposed rigid strip of metal or the like secured to a T-head 15 formed at the outer end of a bar 16. The inner end of the bar is disposed in overlapping relation with a similar bar section 17, the overlapping ends of said bar sections being provided with openings 18 through which bolts 19 may be inserted for securing the sections in longitudinally adjusted position with respect to each other. The sections of the bars are slidably mounted upon the top of the lidder 9 by brackets 20. The inner end of the bar section 17 is forked as shown at 21 and is provided with a pair of spaced rollers 22.

Between the rollers 22 an upwardly extending rod 23 is inserted, said rod having its lower end formed into an eye 24 and through which a threaded rod 25 is freely inserted. The rod 25 extends rearwardly of the machine with one end threadedly engaged to an upper horizontally disposed back guard 26 secured to the frame 5 of the machine and which back guard constitutes a support for attaching the rear tucking member 27. The back guard 26 and the rear tucking member 27 are provided with registering openings 28 and 29, respectively, through which bolts 30 may be inserted for securing the tucking member in vertically adjusted position in order that the same may be adjusted to crates of various heights and so that the rear tucking member may rest upon the upper edge of the rear of the crate and flush with the inner wall thereof, as clearly illustrated in Figures 7, 8 and 9 of the drawings.

The outer ends of the back guard 26 are offset, in a plane forwardly of the guard, as shown at 31 to form abutment for the ends of the rear tucker member 27.

The upper end of the rod 23 is inserted through an opening 33 formed in the forward end of a plate 34 adapted to be secured to the upper portion of the frame of the machine 5 in forwardly or rearwardly adjusted position by means of a row or openings 35 formed at the rear of the plate through which an attaching bolt 36 is inserted. The plates 34 provides a means for adjusting the upper end of the rod 23 forwardly or rearwardly with respect to the machine and the lower end of the rod 23 may also be forwardly or rearwardly adjusted by means of a pair of jam nuts 37 threaded on the bar 25 in spaced relation forwardly and rearwardly of the lower end of the bar 23. A washer 38 is also carried on the threaded bar 25 and interposed between the forward nut and the rod 23. It will thus be apparent that the bar 23 may be inclined forwardly and upwardly from a vertical plane, as clearly illustrated in Figures

7 to 9, inclusive of the drawings, whereby during the downward movement of the lid 9 the forward tucking member 14 will be drawn rearwardly. Accordingly, as the forward tucking member engages the forward edge of the liner 13 the same will be forced downwardly and inwardly of the front side of the crate. By reason of this action the front edge of the liner will be tucked inside of the front side of the crate during the lidding operation.

The manner in which this tucking action is accomplished is more clearly illustrated in Figures 7 and 8 of the drawings.

It is obvious that my invention is susceptible to various changes and modifications in construction without departing from the spirit of the invention or the scope of the appended claims, and I accordingly claim all such forms of the device to which I am entitled.

Having thus described my invention, what I claim as new is:—

1. A liner tucking attachment for crate lidding machines comprising in combination, a reciprocally operated lidder adapted for pressing a lid upon the crate and a tucker carried by the lidder for movement into and out of engagement with one edge of the crate liner whereby to force the liner inwardly of the crate.

2. A liner tucking attachment for crate lidding machines comprising in combination, a reciprocably operated lidder adapted for pressing a lid upon the crate and a pair of liner tucking members disposed at opposite sides of the crate for engaging the edges of the liner whereby to force the same inwardly of the crate.

3. A liner tucking attachment for crate lidding machines comprising in combination, a reciprocably operated lidder adapted for pressing a lid upon the crate and a pair of liner tucking members disposed at opposite sides of the crate for engaging the edges of the liner whereby to force the same inwardly of the crate, one of said members being carried by the lidder for movement therewith and the other of said members being secured in a stationary position.

4. A liner tucking attachment for crate lidding machines comprising in combination, a reciprocally operated lidder adapted for pressing a lid upon the crate, a pair of liner tucking members disposed at opposite sides of the crate for engaging the edges of the liner whereby to force the same inwardly of the crate, one of said members being carried by the lidder for movement therewith and the other of said members being secured in a stationary position and means for moving said movable member inwardly during the downward movement of the lidder.

5. A liner tucking attachment for crate lidding machines comprising in combination, a reciprocally operated lidder adapted for

pressing a lid upon the crate, a pair of liner tucking members disposed at opposite sides of the crate for engaging the edges of the liner whereby to force the same inwardly of the crate, and means for adjusting each of said members in accordance with variations in the size of the crate.

6. A liner tucking attachment for crate lidding machines comprising in combination, 10 a reciprocally operated lidder adapted for pressing a lid upon the crate, a pair of liner tucking members disposed at opposite sides of the crate for engaging the edges of the liner whereby to force the same inwardly of 15 the crate, means for slidably mounting one of said members upon said lidder for horizontal sliding movement and means associated with said member for slidably actuating the same in a direction inwardly of the 20 edge of the crate during the downward movement of the lidder.

7. A liner tucking attachment for crate lidding machines comprising in combination, a reciprocally operated lidder adapted for 25 pressing a lid upon the crate, a pair of liner tucking members disposed at opposite sides of the crate for engaging the edges of the liner whereby to force the same inwardly of the crate, means for slidably mounting 30 one of said members upon said lidder for horizontal sliding movement, rod members extending from the tucker member, and upwardly and forwardly inclined side means for one of said rods whereby to move the tucker 35 inwardly of the edge of the crate during the downward movement of the lidder.

8. A liner tucking attachment for crate lidding machines comprising in combination, a reciprocally operated lidder adapted for 40 pressing a lid upon the crate, a pair of liner tucking members disposed at opposite sides of the crate for engaging the edges of the liner whereby to force the same inwardly of the crate, means for slidably mounting one of 45 said members upon said lidder for horizontal sliding movement, rod members extending from the tucker member, and upwardly and forwardly inclined side means for one of said rods whereby to move the tucker in- 50 wardly of the edge of the crate during the downward movement of the lidder, and means for adjusting the angle of said guide means for regulating the extent of such inward movement.

55 In testimony whereof I hereby affix my signature.

WILLIS H. POYNTER.
